HUMMINGBIRD FEEDER

Harry M. Brown, Jr., 3110 SE. Rex St.,
Portland, Oreg. 97202

Filed June 18, 1968, Ser. No. 12,406

Term of patent 14 years

Int. Cl. D30—02

U.S. Cl. D30—14

FIG. 2

FIG. 1

FIG. 3

FIG. 1 is a front view of a hummingbird feeder in accordance with my new design;

FIG. 2 is a top view thereof; and

FIG. 3 is a bottom view thereof.

The broken line circle at the top of FIG. 1 of the drawing is indicative of a hanging hook, and shown for illustrative purposes only.

I claim:

The ornamental design for a hummingbird feeder, as shown and described.
